UNITED STATES PATENT OFFICE.

CHARLES H. SWARTWOOD, OF BOSTON, MASSACHUSETTS, ASSIGNOR OF ONE-THIRD TO MILES SWARTWOOD, OF SWARTWOOD, NEW YORK, AND ONE-THIRD TO CHARLES B. SWARTWOOD, OF ELMIRA, NEW YORK.

METALLIC RAILWAY-TIE.

1,339,301.

Specification of Letters Patent.

Patented May 4, 1920.

Application filed January 17, 1920. Serial No. 352,036.

To all whom it may concern:

Be it known that I, CHARLES H. SWARTWOOD, a citizen of the United States of America, residing at Boston, in the county 5 of Suffolk and State of Massachusetts, have invented certain new and useful Improvements in Metallic Railway-Ties, of which the following is a specification.

The primary object of the present invention is the provision of a metallic railway tie 10 adapted for mounting the rails upon the roadbed in operative position, provision being made for preventing the tie from breaking under the strains and stresses incident 15 to travel and regardless of the manner of tamping-in the tie upon the roadbed.

A further object of the invention is to provide a tie for railway rails having long life and being easy and cheap to manufacture when at the same time providing resilient seating for the rails, permitting the removal of the rails without displacing the tie whenever desired, the vertical adjustment 20 of the rails being also easily effected upon the tie to compensate for expansion and contraction due to climatic conditions.

A still further object of the invention is the provision of a low-cost tie having rail-supporting end portions provided with 25 floating base members for removably mounting the rails thereon, whereby the rails and bases are readily removable from the tie or secured thereto for elevating therewith as may be found desirable.

With these general objects in view and others that will appear as the nature of the invention is better understood, the same consists in the novel construction, combination and arrangement of parts hereinafter more 30 fully described, illustrated in the accompanying drawings, and then claimed.

In the drawings forming a part of this application, and in which like designating characters refer to corresponding parts 35 throughout the several views:—

Figure 1 is a side elevation of a railway tie formed after the manner of my invention, with rails transversely mounted thereon,

Fig. 2 is a top plan view thereof,

Fig. 3 is an enlarged vertical longitudinal sectional view taken upon line III—III of Fig. 2,

Fig. 4 is a horizontal sectional view taken upon line IV—IV of Fig. 3,

Fig. 5 is a view similar to Fig. 3, with 55 the rail-supporting base shown in elevation secured to the tie for moving therewith,

Fig. 6 is a side elevation of an end portion of the tie with parts broken away, and

Fig. 7 is an end view thereof.

Referring more in detail to the drawings, my invention comprises a tie proper consisting of a body, preferably of cast metal, having end sections or housings 10 adapted for mounting upon the roadbed with an integral connecting web or bridge portion 11, the length of the body being the same length as a standard tie and the cross-sectional area of the housings 10 being substantially the same.

The housings 10 are of tubular form, each having a chamber 12 with a cushioning block 13 of such material as wood, positioned upon the bottom 14 thereof, by spaced transverse ribs 15, the said block being adapted for the 65 resilient seating of an adjustable base 16 thereon for operatively mounting the railway rails transversely upon the tie. Each base 16 is substantially cubical in form, centrally severed transversely into separate 65 halves 18 connected together by a bolt 19 for limiting the amount of separation between 70 said sections of the base.

Frictional holding guides 20 upon the base sections 18 properly position the rails 75 17, between said guides, and transversely of the top 21 of the tie housing 10, with the top plate 22 of the base 16 seated in a corresponding opening 23 in the top 21. A joint 24 is formed between the ledges 25 80 at the opposite edges of the opening 23, and the adjacent edge portions of the plate 22, such connection being adapted to prevent the free flow of water through the opening 23. Extensions 26 at the ends of 85 the ribs 15 act as guides for the vertical movements of the base 16, during operation, the said base being normally unsecured to its housing 10 removably seated through the opening 23 thereof, upon its cushioning 90 block 13.

An adjusting screw 27 projects through the base 16, longitudinally of the chamber 12 being screw-threaded for a portion of

its length having threaded engagement with an opening 28 through the outer section 18 of the base 16 while the inner end of the screw 27 is journaled through an opening 5 29 in the other section 18 of the base, with the head 30 at the inner end of the screw engaging the side thereof, as best illustrated in Figs. 3 and 4 of the drawings. The outer end of the screw 27 freely projects through 10 a vertical slot 31 in the end wall 32 of the housing 10, being furnished with a squared reduced end 33 for turning the screw 27 for drawing the sections 18 of the base 16 toward each other, or releasing them at will. 15 The said bolt 19 holds the lower portions of the base sections 18 against entire separation limiting relative movement thereof as heretofore noted and it will be evident that upon revolving the screw 27, in one 20 direction, the sections 18 will be drawn together, frictionally engaging the guides 20 against the opposite edges of the base flanges 34 of the rail 17, seated upon the top plate 22, between the said guides. The rails 17 25 when positioned upon the bases 16, will be normally secured against creeping by the guides 20 as well as by clips 35 secured to the top plate 22, by bolts 36. Depending flanges 37 at the opposite sides of the plate 30 22, overlie the sides of the housings 10, the bolts 36 preferably extending through said flanges 37.

Under normal conditions, the rails 17 being secured to the bases 16 in the manner 35 described, with said bases positioned upon the blocks 13, provides a strong structure capable of long use and wear, and not likely to get out of repair, it being seen that the base 16, may be readily elevated out of its 40 opening 23, by lifting the rail 17 upwardly which is secured to said base 16 and carrying the same inwardly of the track. When it is desired to elevate the tie body, however, screws 38 are positioned through perforations 39 adjacent the edges of the plates 22 45 for engaging the threaded perforation 40 of the adjacent side portions 25 of the top 21 of the tie as illustrated in Fig. 5 of the drawings, and at which time, the base 16 and tie 50 may be elevated together.

When desiring to slightly raise the rails 17, the screws 27 may be turned in the proper direction for releasing the base sections 18 and disengaging the guides 20 from the 55 rail base 34, so that shims or spacing blocks of the usual form and unnecessary to herein illustrate, may be forced beneath the rails upon the top plate 22 of its supporting base. The slot 31 also provides an outlet 60 for moisture from the chamber 12 of the housing 10 and while the form of the invention herein set forth and described is believed to be the preferable embodiment thereof, it will nevertheless be understood 65 that minor changes may be made therein,

without departing from the spirit and scope of my invention.

What I claim as new and desire to secure by Letters Patent, is:—

1. A railway tie comprising spaced hollow housings adapted for positioning upon the roadbed, a connecting web between the tops of the housings, adjustable bases resiliently seated within said housings projecting through the tops thereof and guides upon 75 said bases transversely of the tie adapted for frictional engagement with the base flanges of rails when operatively mounted upon said bases.

2. A railway tie comprising end housings 80 having openings through the top of the tie, two-part bases positioned within said housings with the tops of the bases substantially flush with the top of the tie, upright guides upon the bases transversely of the tie adapted 85 for frictional engagement with railway rails when operatively positioned upon said bases, adjusting means for the parts of the bases operable at the ends of the tie whereby said guides are adapted for movement toward and away from each other, the ends of the housings being provided with vertical outlets, retaining bolts positioned through the parts of each base adjacent the bottom 90 thereof, and positioning means for the bases 95 upon the bottoms of the housings.

3. A railway tie comprising end housings having openings through the top of the tie, two-part bases positioned within said housings with the tops of the bases substantially 100 flush with the top of the tie, upright guides upon the bases transversely of the tie adapted for frictional engagement with railway rails when operatively positioned upon said bases, adjusting means for the parts of the 105 bases operable at the ends of the tie whereby said guides are adapted for movement toward and away from each other, the ends of the housings being provided with vertical outlets, retaining bolts positioned 110 through the parts of each base adjacent the bottom thereof, positioning means for the bases upon the bottoms of the housings, whereby the bases are normally adapted for removal through said top openings and securing means between the bases and housings 115 whereby the rail may be moved with said bases at will.

4. A railway tie comprising spaced housings, each housing having an opening in the top thereof, and a vertical slot in its outer end wall, a connecting web between the tops of the housings, resilient members within the housings upon the bottoms thereof beneath said openings, a hollow base in two 125 parts mounted upon each resilient member with the tops of the bases substantially flush with the tops of the housings, operating screws swiveled through the inner part of each base and threaded through the outer 130

part having projecting ends outwardly of said slots at the opposite ends of the tie, an upright guide upon each part of each base adapted for the seating reception of 5 railway rails between the guides of each base whereby the guides are adapted for holding engagement with the base flanges of rails in their operative positions transversely of the tie.

10 5. A railway tie comprising spaced housings, each housing having an opening in the top thereof, and a vertical slot in its outer end wall, a connecting web between the tops of the housings, resilient members within 15 the housings upon the bottoms thereof beneath said openings, a hollow base in two parts mounted upon each resilient member with the tops of the bases substantially flush with the tops of the housings, operating 20 screws swiveled through the inner part of each base and threaded through the outer

part having projecting ends outwardly of said slots at the opposite ends of the tie, an upright guide upon each part of each base adapted for the seating reception of 25 railway rails between the guides of each base whereby the guides are adapted for holding engagement with the base flanges of rails in their operative positions transversely of the tie, positioning means for the 30 resilient members and bases within each housing upon the bottom thereof, complementally-formed adjacent edges between the base members and the adjacent edges of said openings, removable connections between 35 the tops of the bases and housings and movement-limiting means connected between the parts of each base beneath the operating screws.

In testimony whereof I affix my signature. 40

CHARLES H. SWARTWOOD.
